SHADE ROLLER BRACKET

Theodore W. Cox, East Orange, and Norman G. Johnston, Pequannock, N.J., assignors to The Nevets Company Inc., Newark, N.J., a corporation of New Jersey

Filed July 25, 1961, Ser. No. 66,062

Term of patent 14 years

(Cl. D21—1)

FIGURE 1 is a side elevational view of a shade roller bracket showing our new design;

FIGURE 2 is a front elevational view looking in the direction of the arrows 2—2 of FIG. 1;

FIGURE 3 is a rear elevational view looking in the direction of the arrows 3—3 of FIG. 1;

FIGURE 4 is a side elevational view showing the side opposite that shown in FIG. 1 and looking in the direction of the arrows 4—4 of FIG. 3;

FIGURE 5 is a top plan view looking in the direction of the arrows 5—5 of FIG. 1; and

FIGURE 6 is a cross-sectional view thereof taken on the line 6—6 of FIG. 1.

We claim:

The ornamental design for a shade roller bracket, as shown and described.
